[57] **CLAIM**

The ornamental design for a straight edge level, as shown and described.

DESCRIPTION

FIG. 1 is a top plan view of the straight edge level showing my new design;

FIG. 2 is a front elevational view thereof;

FIG. 3 is a back elevational view thereof;

FIG. 4 is a bottom plan view thereof;

FIG. 5 is an end view thereof taken from the left of FIG. 2;

FIG. 6 is a substantially enlarged opposite end view thereof; and,

FIG. 7 is an isometric view thereof.

FIG. 1

FIG. 2

FIG. 3

FIG. 4

FIG. 6

FIG. 5
